UNITED STATES PATENT OFFICE

FRANK C. H. STRASBURGER, OF CHICAGO, ILLINOIS.

PACKAGE-LABELING MACHINE.

SPECIFICATION forming part of Letters Patent No. 674,141, dated May 14, 1901.

Application filed July 5, 1900. Serial No. 22,552. (No model.)

To all whom it may concern:

Be it known that I, FRANK C. H. STRASBURGER, a citizen of the United States, residing at Chicago, in the county of Cook and State of Illinois, have invented certain new and useful Improvements in Package-Labeling Machines; and I do hereby declare the following to be a full, clear, and exact description of the invention, such as will enable others skilled in the art to which it appertains to make and use the same.

My invention relates to a novel construction in a package and bottle labeling machine, the object being to provide a machine of simple, durable, and efficient construction which will label almost every size and shape of bottle and package; and it consists in the features of construction and combinations of parts hereinafter fully described and claimed.

In the accompanying drawings, illustrating my invention, Figure 1 is a front elevation of a machine constructed in accordance with my invention. Fig. 2 is a vertical longitudinal section of same on the line 2 2 of Fig. 1. Fig. 3 is a side elevation of same, showing some parts in section. Fig. 4 is a fragmentary front elevation showing the devices for affixing the labels in another position and showing a package in place on the support with the label applied. Fig. 5 is a detail sectional view of a buffer forming part of my machine. Fig. 6 is a horizontal section on line 6 6 of Figs. 2 and 3.

Referring now to said drawings, 1 indicates the frame of my machine, which consists of parallel side plates provided with suitable bearings for shafts, &c., and left partially open to save weight. Mounted in a cross-bar 2, extending across the front of the frame, is a vertically-adjustable table 3, upon which the package to be labeled is supported. Below said table 3 is a vertically-movable rod 4, the upper end 5 of which is square and which is movable in bearings or guides 6 and 7 in cross-bars 8 and 9. Said portion 5 of said rod carries a cross-head 10, upon the outer end portions of which collars 11 are rigidly mounted, each of which is provided with parallel upwardly-extending lips or projections 12, between which the lower ends of arms 13 are pivotally secured. The said arms 13 are provided at their lower ends with inwardly-

extending projections 14, between the lower faces of which and said collars 11 springs 15 are interposed, which serve to normally hold the upper ends of said arms at the outer limits of their motion. The outer faces of said arms are provided with grooves 16, into which stops 17 are adapted to project, said stops being rigidly mounted on each side of the frame and adjustable therein. A bifurcated lever 18, having forked ends 19, engaging said cross-head 10, is rigidly mounted between its ends on a shaft 20, and at its other end carries a lug 21, entering a groove 22 in an eccentric 23, mounted upon the drive-shaft 24 of said machine. The said lever 18 imparts a reciprocating motion to said rod 4, thereby raising and lowering said arms 13, while at the same time said stops 17 and springs 15 swing said arms on their pivots. Said arms 13 are provided at their upper ends with flanges 25, to which arms 26 are bolted, the latter having overhanging portions 27, in which rods 28 are longitudinally movable parallel with said arms 13. The lower ends of said rods 28 are provided with collars 29, to the lower faces of which blocks 30, of a soft resilient material, such as sponge-rubber, are secured. Springs 31 are interposed between said collars 29 and said overhanging portions 27, so that as said blocks 30 are brought into engagement with the package on said table 3 they will exert a yielding pressure thereon. Rigidly mounted on said shaft 20 is an upwardly-extending segmental gear 32, meshing with a partially-toothed pinion 33 on a shaft 34, journaled in bearings in said frame 1. Said shaft 34 carries a V-shaped arm 35, which is held practically rigid therewith by means of a spring 36 and a stop 37. The said arm 35 swings through an arc of about one hundred and eighty degrees and serves to take labels from the label-holder 38 and deliver same to a point immediately over the package to which the label is to be affixed. During its rearward motion a suitable paste is applied to the ends of said arm 35 in a manner hereinafter described. Mounted upon said shaft 24 at one end is a groove-cam 39, of practically heart shape, but modified to impart desired motion to a lever 40, which engages said cam at its free end. At its other end said arm 40 is rigidly secured to a shaft

41, carrying a V-shaped bell-crank lever 42, the free apex end of which is pivotally secured to a second bell-crank lever 43, pivotally secured between its ends to the rear end 5 portion of a receptacle 44 for paste, which is reciprocally movable in guides 45 in the upper end of said frame 1. Journalized in the side walls of said box are two rollers 46 and 47, which are geared together, said roller 46 10 revolving in the paste and feeding same to said roller 47. The shaft of said roller 47 carries a ratchet-wheel 48 at one end, a lever 49, loosely mounted adjacent said roller and carrying a pawl 50, engaging said ratchet-wheel 48. A link 51 connects the free end of said lever 49 with the other arm of said bell-crank lever 43. By means of this mechanism said rollers 46 and 47 are revolved during every forward movement of said paste-box 15 20 25 30 35 40 45 50 55 60 65 70 75 80 85 90 95 100 105 110 115 120 125 130 135 140 ing pads carried by said plungers, said pads consisting of a thick yielding material adapted to conform to the surface of the package to which the label is to be affixed when pressed upon same.

4. In a machine of the kind specified, the combination with the label-feeding mechanism, and the package-support, of devices for affixing said labels comprising vertically-movable and separable arms, carrying longitudinally-movable plungers parallel with said arms, and cushions on the ends of said plungers, said plungers being adapted to exert a yielding pressure on the package to affix the label by means of compressing-pads carried by said plungers, said pads consisting of a thick yielding material adapted to be compressed upon and conform to the contour of the surface upon which said label is to be affixed.

5. In a machine of the kind specified, the combination with the label-feeding mechanism, and the package-support, of devices for affixing said labels comprising vertically-movable and separable arms, carrying longitudinally-movable plungers parallel with said arms, heads on said plungers, and springs interposed between said heads and parts of said arms to normally hold said plungers at the lower limits of their movement relatively to said arms, said plungers being adapted to exert a yielding pressure on the package in affixing the label thereto by means of compressing-pads carried by said plungers, said pads consisting of a thick yielding material adapted to be compressed upon and conform to the contour of the surface upon which said label is to be affixed.

6. In a machine of the kind specified, the combination with the label-feeding mechanism, and the package-support, of devices for affixing said labels comprising vertically-movable and separable arms, carrying longitudinally-movable plungers parallel with said arms, cushioned heads on said plungers, and springs interposed between said heads and parts of said arms to normally hold said plungers at the lower limits of their movement relatively to said arms, said plungers being adapted to exert a yielding pressure on the package in affixing the label thereto by means of compressing-pads carried by said plungers, said pads consisting of a thick yielding material adapted to be compressed upon and conform to the contour of the surface upon which said label is to be affixed.

7. In a machine of the kind specified, the combination with a movable paste-box and a label-support, of devices for transferring paste from said paste-box to said label-support at intervals, comprising a rock-shaft, a lever pivotally mounted thereon, a spring connecting said lever and said rock-shaft, and gearing between said rock-shaft and said paste-box, whereby the movements of said paste-box and said lever are respectively so

timed that said lever will engage a part of said paste-box during its movement, to receive paste and then apply the same to the uppermost label on said support.

70

8. In a machine of the kind specified, the combination with a label-support, a package-support, and devices for transferring labels consecutively from said label-support to a point in vertical alinement with said package-support, of a follower adapted to engage the transferred label and clamp same upon the package on said support, and vertically-yielding plungers adapted to engage said label on each side of said follower and press same upon said package.

75

9. In a machine of the kind specified, the combination with a label-holder, a package-support, and devices for transferring said labels consecutively to said package-support, of devices for applying paste to said transferring devices comprising a receptacle for paste movable in guides on the frame of said machine, a roller carried thereby and partially immersed in said paste, a second roller having surface contact with said first-named roller, a shaft carrying said last-named roller and rigid therewith, a ratchet-wheel rigid on said shaft, a lever loosely pivoted on said shaft and carrying a pawl to engage said ratchet, a rock-shaft journaled in the frame of said machine, a vibrating lever carried thereby, and a bell-crank lever pivoted between its ends on said receptacle and pivotally connected at its ends with said vibrating lever and said lever carrying said pawl respectively, whereby said vibrating lever imparts a pivotal motion to said bell-crank lever and a reciprocating movement to the same and said receptacle, thereby turning said last-named roller at intervals.

85

10. In a machine of the kind specified, the combination with a label-holder, a package-support, and devices for transferring said labels consecutively to said package-support, of devices for applying paste to said transferring devices comprising a receptacle for paste movable in guides on the frame of said machine, a roller carried thereby and partially immersed in said paste, a second roller having surface contact with said first-named roller, a shaft carrying said last-named roller and rigid therewith, a ratchet-wheel rigid on said shaft, a lever loosely pivoted on said shaft and carrying a pawl to engage said ratchet, a rock-shaft journaled in the frame of said machine, a vibrating lever carried thereby, and a bell-crank lever pivoted between its ends on said receptacle and pivotally connected at its ends with said vibrating lever and said lever carrying said pawl respectively, and a link interposed in said last-named connection, whereby said vibrating lever imparts a pivotal motion to said bell-crank lever and a reciprocating movement to the same and said receptacle, thereby turning said last-named roller at intervals.

11. In a machine of the kind specified, the combination with the label transferring and applying devices, of a reciprocating paste-box, devices for moving same, and buffers mounted on the frame of the machine in the path of said paste-box and adapted to be engaged by the latter as it approaches the rearward limit of its motion to cushion it.

12. In a machine of the kind specified, the combination with a label-holder and a package-support, of a rock-shaft, an arm thereon adapted to transfer labels from said label-holder to said package-support, a segmental gear on said shaft, a second rock-shaft journaled in the frame below said first-named rock-shaft, a segmental gear carried by said second rock-shaft and meshing with said segmental gear on said first-named rock-shaft, and means for imparting motion to said last-named rock-shaft.

13. In a machine of the kind specified, the combination with a package-support, a label-support, and plungers vertically movable over said package-support, of a drive-shaft, a cam thereon, a rock-shaft, devices common to said rock-shaft and said plungers and engaging said cam for imparting motion to both, devices for transferring labels from said label-support to said package-support, and devices

carried by said rock-shaft for imparting motion to said label-transferring devices.

14. In a machine of the kind specified, the combination with a package-support, devices for feeding labels above same, and devices for applying said labels, of a drive-shaft, a cam thereon, a rock-shaft, devices carried by said rock-shaft and engaging said cam and said label-applying devices for imparting motion to the latter and said rock-shaft, and devices carried by said rock-shaft for imparting motion to said label-feeding devices.

15. In a machine of the kind specified, the combination of the package-support, devices for feeding labels above same, and devices for applying said labels, of a drive-shaft, a rock-shaft adjacent same, a lever carried by said rock-shaft and engaging said label-applying devices, devices on said drive-shaft engaging said lever for imparting motion to said label-applying devices and said rock-shaft, a rock-shaft carrying said label-feeding devices, and gearing between both said rock-shafts.

In testimony whereof I affix my signature in presence of two witnesses.

FRANK C. H. STRASBURGER.
